UNITED STATES PATENT OFFICE.

ARTHUR P. MANDVILL, OF OLYMPIA, WASHINGTON.

OYSTER-OPENING MACHINE.

Application filed May 8, 1922. Serial No. 559,210.

To all whom it may concern:

Be it known that I, ARTHUR P. MANDVILL, a citizen of the United States, and a resident of Olympia, county of Thurston, 5 and State of Washington, have invented certain new and useful Improvements in Oyster-Opening Machines, of which the following is a specification.

This invention relates to improvements 10 in machines of that type known as oyster openers, and more particularly it relates to machines for separating oysters from their shells, and which are capable of opening the large, eastern oysters, or the smaller, western 15 oysters, grown in the Pacific waters of the United States.

The principal object of this invention is to provide a machine of the above character, whereby the oysters may be delivered automatically from a hopper onto an intermittently moving conveyor belt, whereby they are advanced singly to the opening mechanism which opens the shells and cuts the oysters loose therefrom; the shells and oysters 25 then being delivered into separate containers whereby they may be removed from the machine.

Other objects of the invention reside in the details of construction of the conveyor 30 belt and means for advancing it, and in the mechanism whereby the upper and lower halves of the shells are opened apart and the oysters separated therefrom.

Other objects of the invention reside in 35 the details of construction, and in the combination of parts whereby a compact, efficient and easily operable machine is provided.

In accomplishing these and other objects 40 of the invention, I have provided the improved details of construction, the preferred forms of which are illustrated in the accompanying drawings, wherein—

Figure 1 is a side elevation of an oyster 45 opening machine constructed in accordance with the present invention.

Figure 2 is an end view of the same.

Figure 3 is an enlarged, detail view, showing a portion of the conveyor chain whereby 50 the oysters are delivered from the hopper to the opening mechanism and showing, in elevation, parts of the mechanism whereby the two halves of the shell are opened apart and the oyster cut from the lower shell.

Figure 4 is a sectional view taken on the 55 line 4—4 in Figure 3, particularly illustrating the knife for opening the shells.

Figure 5 is a sectional view of one of the links of the conveyor chain, showing the spring clamps whereby the shells are held 60 in position.

Figure 6 is a detail, side view of the means whereby the oyster is removed from the upper half of the shell after the latter has been separated from the lower half. 65

Figure 7 is a front view of the parts as shown in Figure 6.

Figure 8 is a plan view of the parts illustrated in Figure 6.

Referring more in detail to the drawings—

1 designates, as a whole, the frame structure of the machine wherein the operating parts are mounted, and supported respectively at opposite ends of the frame, is a 75 sprocket wheel 2 and a guide wheel 3 about which is extended a link belt 4, having a horizontally moving upper portion, operating along the top of the frame, upon which the oysters may be advanced from a hopper 80 5, supported by means of a bracket 6 from one end of the frame, to the opening mechanism, presently described, that is mounted adjacent the opposite end of the frame.

The belt 4 comprises a plurality of pivotally connected links, wherein every other link, as designated in Figure 3 as the links 4', has, at its forward side, an extended flange 7 against which the hinged edges of the oyster shells are to be disposed by the operator as they are delivered from the hopper; and, mounted horizontally upon these links, are blocks 8 which, at their opposite ends, as shown in Figures 3 and 4, are provided with clamping fingers 9 whereby the 90 oyster shells disposed upon these links may be yieldingly held in position for delivery to the opening knife.

The hopper 5, which is of a funnel shaped character, has a side opening 10 adjacent 100 the belt, and through this the oysters are delivered. The operator of the machine, who would be stationed at the side, places the oysters properly on the belt as it advances; it being essential that the bottom half of the 105 shell be placed on the under side, and that the hinged part of the shell be disposed against the flanges 7.

The means whereby the conveyor belt, and other parts presently described, are operated comprises a crank shaft 12 that is rotatably supported at the back of the frame 1, parallel with the direction of movement of the belt 4. At one end of this shaft 12, is a sprocket wheel 13 which lies in the same vertical plane as sprocket wheels 14 and 15 that are fixed respectively on shafts 16 and 17 supported within the forward portion of the frame, and a sprocket chain 18 extends about these wheels so that all three shafts may be rotated simultaneously; the shaft 16 being provided, as shown in Figure 1, with a gear wheel 19 whereby a suitable driving device, not shown, may be operatively connected therewith.

Fixed on the shaft 12 is a bevel gear wheel 21 which drives a similar gear 22 that is rotatably supported on a pintle 24 extended from a frame member. To this latter wheel is eccentrically fixed one end of a rod 25 which, at its opposite end, is pivotally fixed to an arm 26 that is swingingly mounted about the supporting shaft 27 of the sprocket wheel 2. The arm 26 carries a ratchet tooth 28 that operates on a ratchet wheel 29 fixed to the shaft 27 in order that, as the wheel 22 revolves, the arm 26 is oscillated to cause the ratchet tooth to engage with the wheel 29 and intermittently, rotatably advance the sprocket wheel 2 so that the belt 4 is likewise intermittently moved forwardly intervals equal to the spacing of the links 4'.

Fixed to the throw portion 12' of the crank shaft 12, are two parallel rods 30 and 31 which extend upwardly and forwardly, as shown in Figures 2 and 5, and at their upper ends are fixed pivotally to the opposite ends of a block 32 which is slidably carried, adjacent its ends, within guide slots 33 in plates 34 and 35 fixed in horizontal, spaced relation upon the frame 1. These slots correspond in shape and direction and each comprises a horizontal, rearward portion and an upwardly and forwardly curved forward portion, as shown in Figures 2 and 4, which are directed in this manner in order that the shell opening knife will operate to the best advantage as will presently be described.

Fixed pivotally to the under side of the cross block 32, by means of a screw 36, is a blade 37 which extends forwardly and downwardly and at its end is slideable along a guide groove 38 in the connecting, or base, plate 39 which supports the flanges 34 and 35. A spring plate 40 is fixed to the block in position to bear against the blade to retain it within the groove. Due to this construction, forward, reciprocal movement of the block 32 causes the forward end of the blade to be advanced along the slot and into the joint between the upper and lower sections 65 of the shells so that the two sections are

pried apart and the cords which connect the oyster with the lower section are severed and the hinge of the shell broken. The movement of the blade is best illustrated in Figure 4, as is also shown in the disposition 70 of the shell within the link of the conveyor chain 4; it being noted that the joint of the shell is on a level with the base of the guide groove 38 and in position that the end of the blade 37 will be advanced thereinto. 75

After the shell has been opened and the oyster cut from the lower half of the shell, it is necessary to lift off the top half of the shell and to cut the oyster therefrom. This is accomplished by mechanism that is best 80 shown in Figures 1, 2, 6 and 7, wherein 42 designates a lever that is pivotally mounted to swing in a vertical plane about a pivot shaft 43. This lever, at one end has a weighted portion 44 which normally will 85 retain the other end of the lever in a vertical position, and this weighted portion is adapted to be operatively engaged by arms 45 and 46 fixed to extend radially from the shaft 17 so that the upper end of the lever is 90 caused to be actuated downwardly in contact with the conveyor chain 4 in synchronism with the periods of rest of the conveyor. At the upper end of the lever 42 are spaced apart prongs 47 and 48, see 95 Figure 6, and fixed thereto are spring fingers 49 which are adapted, when the lever is swung downwardly against the conveyor, to engage with opposite edges of a shell and to carry the latter upwardly as the lever moves 100 upwardly; the half shell being held by these fingers as is illustrated in Figure 7.

52 designates a bracket that is fixed to the end of the frame 1 and which extends upwardly therefrom with a horizontal portion 53 extended to overlie the frame. Mounted slidably within a vertical guide groove 54 in the bracket is a block 55 which is connected with the upper end of a pitman rod 56 which, at its lower end, is fixed eccentrically to a wheel 57 on the end of shaft 16 so that as the shaft rotates, the block is moved reciprocally. Likewise, slidably mounted in a guide way in the horizontal portion 53 of the bracket is a block 58 that is connected by means of a rod 59 with the block 55, so that it will be reciprocated accordingly as the shaft 16 rotates. The block 58 has rollers 60 mounted on its opposite sides, see Figure 6, which are operable with 110 in guide grooves 61 in the bracket arm 53 and these grooves have upturned end portions whereby the block, when the rollers are advanced thereinto, will be tilted upwardly. 115

Fixed to the block 58 is a forwardly extending blade 62 and above this is a somewhat longer stop arm 63 which is adapted to be engaged by the lever 42 as the latter swings upwardly to stop its upward move- 120 125 130

ment, while the knife 62 enters along the inner face of the shell carried by the prongs at the end of the lever. As the block 58 is advanced, the rollers 60, moving into the 5 upwardly inclined portions of the guide slots 61 causes the blade 62, after it has been advanced between the oyster and its shell, to be swung upwardly so that it cuts the cords whereby the oyster is tied to the shell, and 10 this allows the oyster to fall from the shell and into a receptacle 65 that is held within the frame, as shown in Figure 1.

As the block 58 is tilted upwardly, the arm 63 is disengaged from the lever, and the latter is then allowed to continue upwardly to its limit under the influence of its lower weighted end portion. The half shell is removed from the prongs of the lever by its being brought into contact with a pin 67 20 that extends laterally from a post 68 fixed to the frame 1; the pin being in position to engage the shell after the lever is released by the stop arm 63 on the block 58. The shells from the conveyor may be caught 25 in a suitable receptacle 70 at the end of the frame and those from the lever in a receptacle 71 at the forward side.

Assuming that the machine is so constructed, its operation would be as follows: 30 The unshelled oysters are placed within the hopper 5 and, as the conveyor belt 4 advances, the oysters are moved thereby toward the opening mechanism. The operator of the machine stands at one side of the belt 35 and individually places the oysters in proper position within the spring fingers 9 of the links 4'.

In the machine, all the operating parts are synchronized so that the shell opening 40 mechanism operates while the conveyor belt is standing still and so that the knife for removing the oyster from the upper part of the shell is advanced after the lever has been stopped by the arm 63.

45 As the oysters are advanced by the belt to a position alined with the blade 37, the latter is advanced by the reciprocal movement of the block 32 connected by the rods 30 and 31 with the crank shaft 12. The forward edge of this blade enters between the two halves of the shell and pries the shell apart, and, at the same time, cuts the oyster loose from the lower portion. The lever arm 42 is then swung downwardly so that 50 the spring clips at its end engages with the upper half of the shell in such manner that when the lever swings upwardly, it carries that part of the shell and the oyster with it. The block 58 is then advanced so 55 that the arm 63 is extended into the path of the lever 42 to retain the latter in position so that the knife 62 may be advanced between the oyster and the shell. Upward tilting of the block 58, due to the movement 60 of the rollers 60 thereon, into the upwardly

inclined portion of the slot 61, causes the knife to be moved upwardly to cut the oyster from the shell so that it may drop into the receiving receptacle. A following outward movement of the block 58 releases 70 the lever 42 so that it may discharge its shell as previously described. This mode of operation is repeated continuously and with each operation an oyster is separated from its shell.

75 It is apparent that a machine of this character would be relatively inexpensive to operate, could be made very compact and the number of oysters that could be opened thereby would only be limited by the rate 80 at which the operator could place them properly upon the conveyor belt.

Having thus described my invention, what I claim as new therein and desire to secure by Letters-Patent, is:

85 1. A machine of the class described comprising, in combination, a conveyor belt provided with means for retaining un-shelled oysters thereon, a reciprocally movable blade operable to separate the two half shells of 90 the oysters as they are advanced thereto by the belt and for cutting the oysters loose from the lower half shell, a swingingly movable lever operable toward and from the belt, having means thereon for gripping the 95 upper halves of the shells to lift them from the lower halves, a blade operable for cutting the oysters loose from the lifted portion of the shells, means for intermittently advancing the belt, and means for actuating 100 the blades and lever in synchronism with the belt movement.

2. A device of the character described comprising, in combination, a horizontally moving conveyor belt, having links thereof 105 equipped with means for retaining unshelled oysters thereon, a reciprocally movable blade having its end portion disposed in position to be advanced into the oyster shells between the upper and lower halves thereof to separate the halves and to cut the oysters loose from the lower halves, a swingingly mounted lever operable from and against the belt and having spring clips at its ends for gripping the upper halves of the shells whereby the 110 latter may be raised, with the oyster therein, from the lower halves, a reciprocally movable block having a knife thereon adapted to be advanced to cut the oysters from the lifted portions of the shells, means for intermittently advancing the conveyor belt to aline the unshelled oysters carried thereby with the path of the opening blade, and means for actuating the other parts in synchronism with the belt movement.

115 3. A machine of the class described, comprising, in combination, a hopper for receiving unshelled oysters and having a discharge opening, a conveyor belt mounted to receive the oysters from the hopper 120 130

thereon and comprising a plurality of links provided with means for holding the unshelled oysters, a crank shaft, means connected with the crank shaft for intermittently advancing the belt, a reciprocally movable block operatively connected with the crank shaft, a blade fixed to the block and adapted, by reciprocation of the latter, to be projected within the shells advanced thereto by the belt to separate the two halves of the shells and to cut the oysters loose from the lower halves, a swingingly mounted lever, means operated by the crank shaft for actuating the lever toward and from the belt; the lever having spring clips at its end adapted to engage the upper halves of the shells to lift them, with the oysters therein, from the lower halves, a reciprocally movable block operated from the crank shaft, having a stop arm thereon movable into the path of the lever, a knife on the block, means for actuating the block to cause the knife to cut the oysters from the lifted shells and to then disengage the stop arm from the lever, and a pin mounted to engage the shells after the lever has been released to cause them to be removed from the lever.

4. In an oyster opening machine of the character described, the combination with

an oyster opening mechanism, of a conveyor comprising a continuous belt made up of pivotally connected links, with links at regularly spaced intervals provided with spring fingers wherein oysters may be held, and means operating in synchronism with the oyster opening means for advancing the belt intermittently to position the oysters carried by the belt properly to be operated on by the opening mechanism.

5. In a machine of the character described, the combination with an oyster opening device comprising a reciprocally moving blade having a sharpened end operable along a guide slot, and a conveyor comprising a link belt having links at certain intervals provided with spring fingers wherein oysters may be held, a crank shaft operatively connected for reciprocating the blade and means connected with the crank shaft for intermittently advancing the belt to move the oyster holding links into alignment with the blade whereby the latter is caused to enter between the halves of the shell and to cut the oysters from the lower half thereof.

Signed at Seattle, Washington, this 2nd day of May 1922.

ARTHUR P. MANDVILL.
